(57) **CLAIM**

We claim the ornamental design for a portable terminal, as shown and described.

DESCRIPTION

This application is also related to copending U.S. Design application Ser. No. 29/419,270 to the same inventors filed on Apr. 26, 2012.

FIG. 1 is a perspective front view of a portable terminal according to the present invention.

FIG. 2 is a perspective rear view of the portable terminal of FIG. 1.

FIG. 3 is a front view of the portable terminal of FIG. 1.

FIG. 4 is a rear view of the portable terminal of FIG. 1.

FIG. 5 is a top view of the portable terminal of FIG. 1.

FIG. 6 is a bottom view of the portable terminal of FIG. 1.

FIG. 7 is a left side view of the portable terminal of FIG. 1.

FIG. 8 is a right side view of the portable terminal of FIG. 1.

FIG. 9 is a perspective front view of a second embodiment of a portable terminal according to the present invention.

FIG. 10 is a perspective rear view of the portable terminal of FIG. 9.

FIG. 11 is a front view of the portable terminal of FIG. 9.

FIG. 12 is a rear view of the portable terminal of FIG. 9.

FIG. 13 is a top view of the portable terminal of FIG. 9.

FIG. 14 is a bottom view of the portable terminal of FIG. 9.

FIG. 15 is a left side view of the portable terminal of FIG. 9; and,

FIG. 16 is a right side view of the portable terminal of FIG. 9.

The portions shown in broken line are not claimed.
